FIG. 1 is a side elevational view of the combined platform and ramp;

FIG. 2 is a top plan view thereof;

FIG. 3 is a front elevational view thereof;

FIG. 4 is a bottom plan view thereof;

FIG. 5 is a rear elevational view thereof;

FIG. 6 is a perspective view thereof;

FIG. 7 is a side elevational view of a modified form of the design illustrated in FIG. 1;

FIG. 8 is a top plan view thereof;

FIG. 9 is a rear elevational view thereof;

FIG. 10 is a front elevational view thereof;

FIG. 11 is a reverse side elevational view thereof;

FIG. 12 is a bottom plan view thereof;

FIG. 13 is a perspective view thereof.

I claim:

The ornamental design for a combined platform and ramp, as shown and described.
